PILOT FUEL INJECTOR

George Stephen Kammer, Great Bookham,
Leatherhead, EnglandApplication July 10, 1945, Serial No. 604,173
In Great Britain July 12, 1944

2 Claims. (Cl. 299—107.6)

1

This invention relates to fuel injectors for internal-combustion engines in which a small charge of pilot fuel is injected before the main bulk of the fuel at each stroke. An injector of this kind is disclosed in my patent application Serial No. 497,991, filed August 9, 1943, now Patent No. 2,407,610; granted September 10, 1946, and the present invention is directed to a nozzle and associated parts of an injector suitable for use with the pump and other elements of the prior disclosure.

According to the invention the fuel finally leaves the nozzle at the edge of a normally closed valve which is opened periodically by means of the pressure in the fuel pump cylinder.

In a preferred construction the nozzle body terminates in a female conical valve seating and the valve member is formed as a conical shoulder on a cylindrical stem movable axially in the valve body and provided with fuel ducts to convey the fuel to the valve.

With such a form of construction the nozzle and pump can be conveniently combined into a single unit.

The accompanying drawing shows by way of example an injector unit comprising a pump mainly in accordance with the prior specification above referred to and a nozzle in accordance with the present invention, and therein

Figure 1 is an axial section through the unit,
Figure 2 is an axial section at right angles to
the section of Figure 1.

Figure 3 is a transverse section on the line
III—III of Figure 1, and

Figure 4 is a transverse section on the line
IV—IV of Figure 2.

For the purpose of the description the unit will be assumed to be placed vertically with the discharge end at the bottom, though the unit is suitable for use in any orientation.

A pump cylinder 1 contains a plunger 2, the head 3 of which is embraced by a tappet 4 guided in an upward extension of the cylinder 1. A spring 5 urges the plunger to the top position as shown in Figures 1 and 2. The tappet is depressed at the appropriate times by the usual cam (not shown). The plunger 2 can be rotated through a certain angle by means of a rack 6 engaging gear teeth on an enlarged part 7 of the plunger to vary the quantity of fuel injected.

The plunger 2 has a circumferential groove 8, of which the lower edge has a helical part 9 to cooperate with a port 10 in the cylinder wall. At the lower end of the helical edge an axial groove 11 in the plunger provides communication between the circumferential groove 8 and the pressure space 12 of the pump. A cap nut 13 is used for fixing the nozzle body, as will be described later, and has an internal circumferential groove 14 to register with two radial ducts 15, 15 ter-

2

minating in inlet and spill ports 16, 16. The fuel supply enters by sockets 17, 17 (Figure 4) and passes through vertical ducts 18, 18 to the ducts 15, 15.

5 A control port 19 below one of the ports 16 communicates by a duct 20 with one duct 15, part of the duct 20 being of small cross-section to impose considerable resistance to the flow of fuel. The port 10 for main fuel is situated in the cylinder wall the same vertical distance above the control port 19 as the length of the plunger from its bottom edge to the lower edge of the groove 8, and it communicates by a duct 21 with the nozzle.

15 The nozzle body 22 is clamped by the cap nut 13 to the lower flat face of a downward extension of the cylinder 1. A packing washer 23 prevents leakage through the screw thread. The lower end of the nozzle body 22 terminates in a female conical valve surface 24, and the body 22 has a cylindrical bore for axial movement therein of a valve member.

20 The valve member is constituted in part of a stem 25 in which longitudinal grooves are cut. One groove 26 is longer than the others marked 27. There may be five grooves 27 in a typical case, though the drawings show only three. Usually one groove 26 is sufficient, as will be clear from the method of operation. The lower end 25 of the stem 25 terminates in an enlarged head 28, and the upper end has a screw thread.

25 Another part of the valve member is a sleeve 29 fitting tightly on the stem 25 and abutting at the lower end against the head 28. The sleeve 29 is firmly secured in place by a bush 30 and nut 31. The grooves 26 and 27 cooperate with the sleeve 29 to form fuel ducts. A transverse hole 32 in the upper edge of the sleeve 29 provides communication between the top of the groove 26 and the space around the bush 30, which is in direct communication with the pressure space 12 of the pump. Radial holes 33, 33 through the sleeve 29 provide communication between the upper parts of the grooves 27, 27 and an annular groove 34 in the nozzle body 22. The groove 34 communicates in turn by a duct 35 with an annular groove 36 in the upper face of the body 22, which registers with the duct 21.

30 The lower end of the sleeve 29 is enlarged and has a conical face 37 to fit the seating 24. The valve is normally held closed by the upward pressure of a helical spring 38 against the nut 31. Jet holes 39, 39 are drilled through the sleeve 29 at about the same obliquity as the faces 24 and 37 to provide communication between the lower ends of the grooves or ducts 26 and 27 and the cooperating surfaces 24 and 37.

35 Operation of the injection unit described may be considered as commencing from the rest position shown in Figures 1 and 2. The pressure

space 12 is in communication through the ducts 15 and 18 with the fuel supply and is thereby maintained full of fuel. After the plunger 2 has descended a short distance it covers the ports 16, 16 and so cuts off this communication. Pressure in the space 12 immediately rises and is exerted through the space around the upper part of the valve 25, 29, 30, the groove 32, the duct 26 and the corresponding nozzle orifice 39 above the valve face 37. The valve is thereby opened against the effect of the spring 38, and injection commences.

At the same time a certain proportion of the fuel will leak through the control orifice 19 and duct 20 back to duct 15 and the supply. The amount of fuel thus by-passed governs the amount of fuel which is discharged, through nozzle orifice 39, into the engine combustion space, that is, it governs the rate of pilot fuel discharge as well as the pressure in the pumping space.

At a certain point in the descent of the plunger 2 its lower edge covers the control port 19, but at the same time the lower edge of the groove 8 uncovers the port 10. The leakage through the control port 19 and duct 20 ceases, and all the fuel displaced by the plunger is delivered to the combustion space, a part of it as before through the groove 32, the duct 26 and one of the nozzle orifices 39, but the major part of it through the port 10, the duct 21, the groove 36, the duct 35, the groove 34, the holes 33, 33, the grooves 27, 27 and the remainder of the nozzle orifices 39.

Thus an additional quantity of fuel, equivalent to the entire displacement of the pump plunger can now find its way into the engine combustion space, at the main rate of fuel discharge determined by the area of the plunger and the rate of lift of the pump operating cam. This quantity, obviously, is substantially greater than the initial rate, or pilot rate of discharge.

The plunger continues its stroke downwards to the full amount determined by the operating mechanism, but before the stroke is quite completed, the helical edge 9 uncovers one of the ports 16, whereby pressure in the space 12 is relieved, the remainder of the stroke merely serving to push fuel back to the supply. The spring 38 closes the valve 24, 31, since there is no pressure available to keep it open, and injection ceases abruptly. The duration of injection is determined by the time elapsing between the uncovering of the ports 10 and 16, and this again is determined by the position of the helical edge 9 due to rotation of the plunger 2 by means of the rack 7. The drawings show the plunger set for full load or maximum injection.

It will be seen that the arrangement disclosed provides pilot injection at a reduced rate and main injection at a substantially higher rate. The rate of fuel discharge at any instant depends on the cross-sectional areas of the discharge orifices conveying fuel to the combustion space and of the leakage path returning fuel to the supply, the rate of lift of the operating cam and the area of the pump plunger, but it is independent of the engine speed, which only governs the injection pressure.

There is no interval between pilot and bulk injection as in some known forms of injector, the valve remaining open continuously from the commencement of pilot injection to the conclusion of bulk injection.

Where reference is made above to times and rates, these must of course be understood in terms of crank angle, as is usual in internal combustion engine practice.

5 What I claim is:

1. A fuel injection nozzle for an internal combustion engine which includes a valve seating, a valve member having a face to cooperate with the seating, a stem joined to the valve member with longitudinal surface grooves therein, a sleeve tightly fitting and fixed to the stem to constitute the grooves into fuel ducts, holes through the sleeve communicating with the ducts near the said face of the valve member to constitute nozzle orifices, a surface on the valve member exposed to fuel pressure exerted in a direction to move the valve member in the direction of flow of the fuel in the ducts and thereby to open the valve, and resilient means opposing the said movement to keep the valve normally closed, said valve face being located adjacent said sleeve holes whereby the fuel finally leaves the nozzle orifices between the valve seating and the face on the valve member and substantially clear of said seating and face.

2. A fuel injection nozzle for an internal combustion engine, said nozzle including fuel supply ducts communicating with two different discharge ports of a fuel pump, a valve seating, a valve member having a face to cooperate with the seating, a stem joined to the valve member with longitudinal surface grooves therein, a sleeve tightly fitting the stem to constitute the grooves into fuel ducts, holes through the sleeve communicating with the ducts near the said face of the valve member to constitute nozzle orifices, communication means between some of the said ducts and one discharge port of the fuel pump, at least one other of the said grooves being longer than the remainder, communication means between said longer duct and the other discharge port of the fuel pump, a surface on the valve member exposed to fuel pressure from either group of ducts, whereby the valve member is moved by the fuel pressure in the direction of flow of the fuel in the ducts, and resilient means opposing the said movement to keep the valve normally closed, the valve being so located that the fuel finally leaves the nozzle orifices between the valve seating and the face on the valve member.

GEORGE STEPHEN KAMMER.
